UNITED STATES PATENT OFFICE

LOUIS OPPENHEIM, OF NEW YORK, N. Y.

WATER-CLOSET SEAT.

No. 823,646.

Specification of Letters Patent.

Patented July 21, 1903.

Application filed July 3, 1907. Serial No. 382,086.

To all whom it may concern:

Be it known that I, LOUIS OPPENHEIM, a citizen of the United States, residing at New York city, Manhattan, county and State of New York, have invented new and useful Improvements in Water - Closet Seats, of which the following is a specification.

This invention relates to a water closet seat which is so constructed that the sections 10 of which the seat is composed are thoroughly interlocked and that the joints between said sections cannot open under the influence of shrinkage, strain or moisture.

In the accompanying drawing: Figure 1 is a plan of my improved water closet seat; Fig. 2 an end view thereof; Fig. 3 an enlarged section on line 3—3, Fig. 1; Fig. 4 an enlarged end view of one of the side pieces, and Fig. 5 a similar view of one of the end pieces.

20 The closet seat is composed of two wooden side sections 10, and two interposed wooden end sections 11, as usual. The side sections 10 are provided along each end of their inner edge with a tongue 12 which is made flaring 25 in cross section, (Fig. 3), and wedge-shaped in longitudinal section or face view, (Fig. 4). The taper of the tongues is preferably such that they gradually widen towards the outer edge of the end sections, where they attain 30 their maximum cross section. Each tongue 12 is provided with a socket for the reception of a locking pin 13, pressed outward by a spring 14.

The end sections 11 have at each edge a 35 groove 15 which is so shaped that it will accommodate tongue 12. That is to say, each groove is undercut in transverse section, (Fig. 3), and tapers in longitudinal section or face view, (Fig. 5). Into each groove 40 opens a socket 16 adapted to become alined with pin 13, so as to receive the same.

In assembling the parts, the side sections 10 are placed into parallelism and at a distance apart equal substantially to the length 45 of the end sections. The latter are arranged at right angles to the side sections and

grooves 15 are brought into engagement with the inner ends of tongues 12. The end sections are now moved outward along such tongues, (the pins 13 being temporarily depressed by hand), until the outer edge of the end sections is flush with the corresponding edge of the side sections, when further movement will be prevented by the tapering shape of the tongues and grooves. When the end 55 sections have thus arrived at their correct position, sockets 16 will become alined with the pins 13, (which have meanwhile been released), so that the pins will be projected by their springs 14, into the sockets. In this 60 way all the parts of the seat will become permanently interlocked and any spreading of seams under the influence of heat or moisture is prevented.

I claim:

1. In a closet seat, side sections each having sockets, end sections between the side sections, each end section having a socket upon each side for alinement with the corresponding sockets of the side sections, and locking devices carried by one set of sockets for automatic projection into the other set of sockets when the sections are assembled to lock the sections together permanently, said locking devices being wholly confined 75 within the assembled sections against manipulation.

2. In a closet seat, side sections having wedge-shaped tongues provided with sockets, end sections having wedge-shaped grooves 80 upon each side and each provided with a socket, and spring pressed locking pins seated in the sockets of the side sections for projection into the sockets of the end pieces when the sections are assembled to lock the sections 85 together permanently.

Signed by me at New York city, (Manhattan), N. Y., this 1st day of July, 1907.

LOUIS OPPENHEIM
